UNITED STATES PATENT OFFICE

CLAUD DRAKE, OF RICHMOND HEIGHTS, MISSOURI

CONNECTER FOR MULTIPIECE RAILS

Application filed December 24, 1930. Serial No. 504,499.

This invention relates to a connecter that is intended to be used for joining multi-piece rails of the type that consist of two parallel insulated sections which form the opposite 5 sides of an electric circuit.

One object of my invention is to provide a connecter for rails of the type mentioned, which, in addition to establishing proper electrical connection between the similar sections 10 of two abutting rails, will also securely hold the rails against relative movement in a vertical direction, in a lateral direction and in a longitudinal direction.

Another object is to provide a rail connecter of the character mentioned, that is inexpensive to manufacture and which can be applied to the rails quickly and without the necessity of manipulating nuts or other threaded fastening devices.

20 I have herein illustrated my invention embodied in a connecter for a toy train track rail of the kind disclosed in my United States Patent No. 1,605,521, dated November 2, 1926, but I wish it to be understood that my 25 invention is applicable to a connecter for any kind of a rail that comprises two parts or sections through which an electric current is flowing, and which are insulated from each other in order to prevent the current from 30 short-circuiting or passing from one section of the rail to the other section of the rail.

Figure 1 of the drawings is a side elevational view, partly in vertical section, illustrating my improved connecter arranged in 35 operative engagement with two longitudinally aligned rails whose terminal ends are disposed in abutting or approximately abutting relationship.

Figure 2 is a transverse sectional view, 40 taken on the line 2-2 of Figure 1.

Figure 3 is a perspective view of the connecter disassembled from the rails.

Figure 4 is a top plan view of the structure shown in Figure 1.

45 Figure 5 is a perspective view of one of the tie bars.

In the drawings A and A' designate two longitudinally aligned or abutting rails, each of which is made up of two identical sections of such cross-sectional shape that when

they are arranged in parallel relation, they will co-operate with each other to produce a rail having a horizontally-disposed base portion, a vertically-disposed web portion and a head that will serve as a tread for a 55 wheel. Said sections form the opposite sides (positive and negative) of an electric circuit, and said sections are insulated from each other by an insulator α , as shown in Figure 2. The two sections of the rail are rigidly connected together by rivets γ , or any other suitable means that will maintain said sections in rigid relationship and prevent the electric current from passing from one section to the other. 60

The connecter that I have devised for joining two rails of the character mentioned has provision for establishing proper electrical connection between the longitudinally aligned sections of two abutting rails A and 70 A' and also provision for preventing said rails from separating and from moving vertically or laterally relatively to each other.

In the preferred form of my invention herein illustrated said connecter comprises 75 a device B, shown in Figure 3, constructed so as to bridge the joint between the rails A and A' and embrace the base flanges and vertical webs of said rails, and it comprises one or more tie bars C, shown in Figure 5, 80 disposed transversely of the joint between the rails and maintained in interlocking engagement with the rails by the device B.

In the form of my invention herein illustrated the device B is made up of two opposed members or side members constructed of metal and combined with an insulator 1 that prevents electric current from passing from one of said side members to the other side member. As shown in Figure 3, each 85 of the side members just referred to has a substantially horizontally-disposed, channel-shaped portion 2 whose top leg has an upwardly-projecting flange 3 and whose bottom leg has a downwardly-projecting flange 4. When said side members are arranged in 90 opposed relation the horizontally-disposed, channel-shaped portions 2 of same co-act with each other to form in effect a sleeve that 95 is adapted to receive the base flanges of two 100

abutting rails A and A', and the upwardly-projecting flanges 3 on said side members coact with each other to form in effect fish plates or splice bars that bear against the webs of the rails and extend across the joint between the terminal ends of the rails. The depending flanges 4 on said side members embrace the insulator 1, and said flanges 4 are rigidly connected together, preferably by means of rivets 5 that pass transversely through said flanges and through the insulator 1. In order that the rivets 5 will not form a path through which the electric current can flow from one side member to the other side member of the device B, insulators 6 are combined with the rivets 5 in such a way that at least one end portion of each rivet will be maintained out of electrical contact with one of the flanges 4 through which the rivet passes. The depending flanges 4 on the device B are preferably made of such depth that when the connector is in use the bottom edges of said flanges will contact with the supporting surface on which the rail ties 2 rest, and thus effectively prevent the ends of the rails A and A' from deflecting under load, i. e., when a wheel travels over the joint between the rails.

The tie bar C, previously referred to, is also preferably constructed of metal, and is intended to be arranged transversely of the joint between the rails A and A' and held in interlocked engagement with said rails by means of the device B. Preferably two tie bars C are used and slots 7 are formed in the base flanges of the rails, as shown in Figure 4, so as to receive lugs or angularly-disposed projections 8 on the tie bars. After the rails A and A' have been arranged in abutting or approximately abutting relationship, the tie bars C are applied to the bottom faces of the flanges of the rails in such a way that the lugs or extensions on said tie bars will project upwardly through the slots 7 in the base flanges of the rails. Thereafter, the device B is moved longitudinally of the rails into a position where it bridges the joint between the rails and clamps the tie bars C to the base flanges of the rails. The preferred method of using my improved connector is to first slide the device B over the end portion of one of the rails, for example, the rail A, and move said device longitudinally of the rail into the position shown in broken lines in Figure 1. The tie bars C are next interlocked with the base flange of the rail A by inserting the lugs 8 on said tie bars in the slots 7 in the base flange of said rail, after which the device B is moved longitudinally of the rail A in the opposite direction far enough to lap over said tie bars and retain them in position. The other end portions of the tie bars C are then interlocked with the base flange of the rail A', after which the device B is moved longitudinally in a direc-

tion to embrace the end portion of the rail A', and thus securely hold the tie bars C in interlocked relationship with the two rails, as shown in full lines in Figure 1. To disconnect or disassemble the rails A and A' it is only necessary to slide the device B longitudinally into such a position that the tie bars can be disconnected from the base flanges of the rails.

A rail connector of the construction above described makes it possible to join two multi-piece abutting rails without manipulating nuts, screws or other threaded fastening devices; it establishes proper electrical connection between the longitudinally-aligned sections of the rails without danger of short circuits being produced, and it securely holds the abutting rails against relative movement either vertically, laterally or longitudinally. While such a connector is not limited to use with toy train track rails, it is particularly adapted for this purpose on account of the ease with which it can be applied to or removed from the rails, and on account of its low cost of manufacture, it being preferable to construct the device B from two identical sheet metal stampings that can be shaped and combined by simple punch press operations, and it also being preferable to use a sheet metal stamping to form the tie bars C.

Having thus described my invention, what I claim as new and desire to secure by Letters Patent of the United States is:

1. A means for joining rails of the type that consist of two insulated metallic sections which form the opposite sides of an electric circuit, consisting of a device adapted to be arranged in engagement with the ends of abutting rails and having provision for mechanically connecting the rails together and maintaining the opposite sections insulated from each other.

2. A means for joining rails of the type that consist of two insulated metallic sections which form the opposite sides of an electric circuit, consisting of a device adapted to be arranged in engagement with the ends of abutting rails and having provision for holding said rails against relative movement, and means combined with said device for establishing electrical connection between the co-acting longitudinally-aligned sections of the rails which form the opposite sides of the circuit.

3. A means for joining rails of the type that consist of two insulated metallic sections which form the opposite sides of an electric circuit, consisting of a device adapted to be arranged in engagement with the ends of abutting rails and having provision for holding said rails against relative movement either vertically, laterally or longitudinally, and means combined with said device for establishing electrical connection between the co-acting longitudinally-aligned

sections of the rails which form the opposite sides of the circuit.

4. A means for joining rails of the type that consist of two insulated metallic sections which form the opposite sides of an electric circuit, consisting of a device constructed to embrace the base flanges of abutting rails and bridge the joint between same, said device comprising opposed side members that are insulated from each other.

5. A means for joining rails of the type that consist of two insulated metallic sections which form the opposite sides of an electric circuit, consisting of a device constructed so as to bridge the joint between abutting rails and bear upon the base flanges and webs of said rails, said device comprising opposed side members that are insulated from each other.

6. A means for joining rails of the type that consist of two insulated metallic sections which form the opposite sides of an electric circuit, consisting of a device constructed to receive the base flanges and webs of abutting rails and having provision for preventing said rails from pulling apart endwise, said device also having provision for establishing proper electrical connection between the respective longitudinally aligned sections of the rails.

7. A means for joining rails of the type that consist of two insulated metallic sections which form the opposite sides of an electric circuit, consisting of a device constructed to receive the ends of abutting rails and bridge the joint between the same, and a tie bar extending across the joint between the rails and held in engagement with the rails by said device.

8. A means for joining rails of the type that consist of insulated metallic sections which form the opposite sides of an electric circuit, consisting of a tie bar extending across the joint between abutting rails and interlocked with the rails, and a device telescoped over the ends of the rails and over said tie bar for holding said tie bar in operative engagement with the rails and for maintaining said rails in longitudinal alignment with each other.

9. A means for joining rails of the type that consist of insulated metallic sections which form the opposite sides of an electric circuit, consisting of a device made up of two opposed metallic side members insulated from each other and constructed to form a sleeve that receives the base flanges of abutting rails and act as fish plates that engage the webs of the rails, and a means that co-acts with said device to prevent the rails from pulling apart endwise.

10. A connector for joining abutting rails of the type referred to, consisting of a device constructed to receive the base flanges and webs of abutting rails and composed of two

opposed side members, depending portions on said side members joined together, an insulator arranged between said depending portions, a tie bar extending across the joint between the rails and held in engagement with same by said device, and means for interlocking said tie bar with the rails at opposite sides of the joint between the rails.

11. A connector for joining abutting rails of the type mentioned, consisting of a device adapted to be telescoped over the end portions of the rails so as to bridge the joint between the same, said device being composed of two opposed side members having substantially horizontally-disposed, channel-shaped portions whose top legs have upwardly-projecting flanges and whose bottom legs have downwardly-projecting flanges, an insulator positioned between the downwardly-projecting flanges of said side members, and devices passing through said insulator and the flanges between which it is positioned for connecting said side members together.
